(57) **CLAIM**

The ornamental design for a magazine surround, as shown and described.

DESCRIPTION

FIG. 1 is a front view of my design;

FIG. 2 is a left side view thereof;

FIG. 3 is a top view thereof;

FIG. 4 is a top left elevation view thereof; and,

FIG. 5 is a right rear perspective view thereof.

My magazine surround is characterized by the smooth esthetic interface it provides between bottom portion of a pistol grip and the exposed metal flange of an extended ammunition magazine.
